NONLOCKING DOORKNOB LATCH SET

Robert C. Cerf, Jr., Los Angeles, Calif., assignor
to Hollymade Hardware Manufacturing Company, Los Angeles, Calif., a corporation of California

Application December 30, 1948, Serial No. 68,213

3 Claims. (Cl. 292—169)

1

This invention relates to a door knob latch set and in particular to an improved non-locking knob operated "through door" latch set.

One object of the invention is to provide an improved non-locking door knob latch set. Another object is to provide a door knob latch set which is adaptable to fit doors of different thickness. Another object is to provide means in a door knob latch set for equalizing the protruding length of the knob spindles on the two sides of the door irrespective of the thickness of the door.

These and other objects are attained by my invention which will be understood from the following description, reference being made to the accompanying drawings in which:

Figure 1 is a top plan view, partly in section, showing a preferred form of my invention;

Figure 2 is a cross-sectional view taken on the line 2—2 of Figure 1;

Figure 3 is a cross-sectional view taken on the line 3—3 of Figure 1;

Figure 4 is a cross-sectional view taken on the line 4—4 of Figure 1;

Figure 5 is a cross-sectional view taken on the line 5—5 of Figure 2;

Figure 6 is a cross-sectional view taken on the line 6—6 of Figure 2;

Figure 7 is an enlarged cross-sectional view showing the rotatably attached end of the equalizing screws;

Figure 8 is a perspective view showing the knob and spindle assembly;

Figure 9 is a perspective view showing a half portion of the retractor housing; and

Figure 10 is a perspective view showing the opposite half retractor housing.

The preferred form of my invention shown in the drawings consists of a die-cast cylindrical body 11 made in right and left half portions 13 and 12 which are adapted to be fastened together by the assembly screws 14 whose heads are countersunk in the countersunk holes 15 of the right half portion 13 and which are threaded into the threaded assembly holes 16 in the left half portion 12 to form the cylindrical body 11. The cylindrical body half portions 12 and 13 are each provided with a bearing hub 17 in which the knob spindles 18 are mounted for turning. The hubs are each provided with a retaining key slot 19 adjacent a boss 20 at the end of the respective cylindrical half portions 12 and 13, each of which is arranged to hold a hair pin spring 21 which is attached to the body portion in a radial groove 22, by a headed screw 23 in a threaded hole 24. The hollow interior of the

2

cylindrical body 11 is arranged with guide ridges 25 for the longitudinal movement of a retractor 26 having a thrust plate partition 27. The generally rectangular shaped retractor is mounted to slide on the pin 28 which is clamped at one end between the pin bosses 31 of the two half portions 12 and 13 in the half cylindrical grooves 29 and projects into the cavity of the body 11. A coil compression spring 30 is provided around the pin, one end abutting the pin bosses 31 and the other end abutting the underside of the thrust plate partition 27 of the retractor 26 so that the retractor is normally thrust outwardly with the fingers 32 protruding slightly through the peripheral window 33 in the wall of the cylindrical body 11.

The fingers 32 are adapted to engage the latch bar under the lugs 34 in the end of the latch bar 35, so that the latch bolt may be depressed without actuation of the retractor or knobs. The latch bar 35 extends from the latch bolt 36 which is arranged to slide within the cylindrical latch bolt casing 37 which is mounted in a bored hole in the edge of the door D by mounting screws (not shown) in the end plate 38. The opposite end of the casing 37 is attached by the lugs 39 which extend from the end closure plate 40. The lugs 39 are arranged to slide under the margins 41 of the peripheral window 33 in the cylindrical body 11, with the end walls 42 of the latch bolt casing 37 abutting the outside face of the margins 41. This arrangement permits adjusting the position of the latch bolt casing longitudinally of the cylindrical body 11 which adjustment is desirable and necessary when the holes drilled in the door in which the set is to be installed are not symmetrically located or not accurately aligned. This adjustability also permits the centering of the latch bolt in the edge of the door regardless of its thickness and irrespective of the longitudinal positioning of the body 11 in its mounting hole in the door.

The retractor 26 is actuated by rollbacks 44 arranged on the inner ends of the spindles 18. A rollback is formed by cutting away about one-half of the periphery of the tubular spindle at the free or inner end of the spindle, for a short distance back from the end of the spindle, the longitudinal edges of the remaining half cylinder 45 pressing upon the thrust plate partition 27 alternately depending upon the direction of rotation of the knobs 45. Each tubular spindle 18 is provided with a peripheral key slot 46 extending, for example, one-half the circumference of the spindle, which key slot is adapted to be engaged

by the retainer keys 47 which fit in the retainer key slots 19 and are normally held in the slot by the hair pin springs 21 in the holes 49 through the keys. The slots are made long enough to permit the desired turning of the knobs to effect retraction of the latch bolt. The spindle 18 is attached in any suitable manner to the knob 45, which is preferably provided with a finish hub 48 which telescopes over the spindle for a portion of its length adjacent the knob.

The cylindrical body 11 is adapted to be mounted in the door in a drilled hole through the door connecting with the smaller hole bored at right angles thereto from the edge of the door for the latch bolt casing. The cylindrical body 11 is held in place within the hole in the door by an attached clamping plate 50 on one side of the hole and a loose clamping plate 51 on the opposite side, the clamping plates being larger than the hole so that they engage the margins. The attached clamping plate 50 is movable relative to the end of the cylindrical body by means of long headed screws 54 which are rotatably attached in the holes 55 in the plate 50 by means of a washer 56 over which the end 53 of the screw 54 is riveted. The screws 54 are engaged in the threaded holes 57 in the left half portion 12 of the cylindrical body 11, extension bosses 58 being provided on the end of the cylindrical body. The unthreaded portion of the long headed screws 54 is adapted to turn freely in the holes 59 in the right hand half portion of the cylindrical body, the end of the screws being slotted so that they may be turned from the right hand side of the set. A shoulder 60 under the head limits the outward movement thereof, corresponding to the maximum extension of the clamping plate 50 from the cylindrical body 11.

The other clamping plate 51 is removably attached to the right hand half portion 13 by means of screws 62 in the threaded holes 63 in the end of the right portion of the cylindrical body 13, the heads of the screws 62 holding the clamping plate 51 against the wood of the door bordering the hole in which the cylindrical body is mounted.

Rosettes 65 having turned rims 66 which are arranged to frictionally engage the outer edges of the clamping plates 50 and 51 are provided, these rosettes being also provided with sleeves 67 which telescope over the hubs 48 of the knobs 45, completely covering the spindles regardless of the extent of protrusion from the door faces.

The spindles and attached knobs on both sides of the door are releasable from the respective sides of the door by first releasing the frictionally held rosette and further telescoping its sleeve over the hub of the knob to gain access to the retainer key 47 through the window 52 of the clamping plate. By means of a screw driver or similar tool, the retainer key 47 is raised, which releases it from the peripheral key slot 46 in the spindle 18 so that the knob and spindle may be withdrawn from the bearing hub 17.

The means for clamping the cylindrical body to the door at the margins of the clamping plates so that their positioning may be adjusted from one side in order to equalize the protrusion of the knobs may be utilized on doorknob sets having other latch retracting means and/or locking means.

The advantages of my invention will be apparent. At the time of installation, knob latch sets must be readily adjustable for use on doors of different thicknesses and it is desirable to have

the knobs extend on their spindles for equal distances from the door on the two sides. By means of the adjustment of the position of the attached clamping plate 50, the cylindrical body may be centered in the mounting hole in the door. When the removable clamping plate 51 is then attached on the opposite side by the screws 62, the spindles and knobs extend for equal distances from the door faces. The retractor is independently operated by the rollbacks on both spindles so that only one knob is turned in retracting the latch bolt. The bolt is free to be depressed without actuating the retractor or knob mechanism. The knob and attached spindles may be removed from either side of the door independently of the knob and spindle on the opposite side and if desired, one knob may be left off entirely and a plate rosette may be used to cover the unused spindle opening. By making the cylindrical body by die-casting to accurate mold dimensions, the assembly is rigid, and the knobs are accurately aligned in the long bearing hubs so that even after long use, the knobs and spindle do not wobble. In the preferred construction shown, no mounting screws for either the knobs or for the body are visible from the sides of the doors, thus providing a neat appearance, avoiding the showing of screw heads, and preventing unwarranted tampering with the knob set.

I claim:

1. In a door knob latch set having a cylindrical body adapted to be mounted in a bored hole in a door, with bearing sleeves, spindles and attached knobs extending from opposite ends of said body; means to clamp said body to a door in which it is mounted comprising a pair of clamping plates, each having an axial hole and being adapted for sliding longitudinally on said bearing sleeves, said plates being larger than said body and one of said plates being permanently attached to one end of said body but adjustably spaced away axially from said body by means accessible only from the opposite end of said body; and means for attaching said other clamping plate to the opposite end of said body.
2. In a door knob latch set having a cylindrical body adapted to be mounted in a bored hole in a door, with spindles and attached knobs extending from opposite sides thereof; means to clamp said body to a door in which it is mounted comprising a pair of clamping plates each having an axial hole for a spindle, said plates being larger than said body, one of said plates being permanently attached but adjustably spaced away from said body; and means for attaching and spacing said attached clamping plate consisting of spacing screws mounted in threaded holes in said body, the headed ends of said screws being accessible from the end of said body opposite said attached clamping plate, the other ends of said screws being rotatably held in said attached clamping plate; the other clamping plate being held in clamping relation with said first clamping plate by screws in threaded holes in the end of said body.
3. In a door knob latch set having a cylindrical body adapted to be mounted in a bored hole in a door, with bearing sleeves, spindles and attached knobs extending from opposite ends of said body; means to clamp said body to a door in which it is mounted comprising a pair of clamping plates, each having an axial hole and being adapted for sliding longitudinally on said bearing sleeves, said plates being larger than said body and one of said plates being permanently

70

attached to one end of said body but adjustably spaced away axially from said body by attaching screws swivel-attached at one end to said plate, said screws being threadedly engaged in threaded holes in said body, the unattached ends of said screws being accessible only from the end of said body opposite said attached plate; and screw means for attaching said other clamping plate to the opposite end of said body.
